(57) **CLAIM**

The ornamental design for a respirator protector case, as shown and described.

DESCRIPTION

FIG. 1 is a front perspective view of the design of the present invention for a respirator protector case;

FIG. 2 is a rear perspective view of the respirator protector case illustrated in FIG. 1;

FIG. 3 is a front view of the respirator protector case illustrated in FIG. 1;

FIG. 4 is a top view of the respirator protector case illustrated in FIG. 1;

FIG. 5 is a bottom view of the respirator protector case illustrated in FIG. 1;

FIG. 6 is a left side view of the respirator protector case illustrated in FIG. 1;

FIG. 7 is a right-side view of the respirator protector case illustrated in FIG. 1; and,

FIG. 8 is a rear view of the respirator case illustrated in FIG. 1.

The broken lines illustrate portions of the respirator protector case and form no part of the claimed design.

1 Claim, 8 Drawing Sheets
